CLAIM

The ornamental design for combination liquid flow conducting transparent canister and cross tube assembly for liquid filters, substantially as shown.

DESCRIPTION

FIG. 1 is a front perspective view of a combination liquid flow conducting transparent canister and cross tube assembly for liquid filters, showing my new design;

FIG. 2 is a front elevational view thereof;

FIG. 3 is a side elevational view thereof, as it would be viewed from either side of FIG. 2;

FIG. 4 is a top plan view thereof; and

FIG. 5 is a bottom plan view thereof.

FIG-1.FIG-2.FIG-3.FIG-4.FIG-5.
